Patented Mar. 5, 1918.

UNITED STATES PATENT OFFICE.

DAVID E. EWING, OF HARTINGTON, NEBRASKA.

ADVERTISING DISPLAY-BOARD.

1,257,989.

Specification of Letters Patent. Patented Mar. 5, 1918.

Application filed January 25, 1917. Serial No. 144,448.

To all whom it may concern:

Be it known that I, DAVID E. EWING, a citizen of the United States, residing at Hartington, in the county of Cedar and 5 State of Nebraska, have invented certain new and useful Improvements in Advertising Display-Boards; and I do declare the following to be a full, clear, and exact description of the invention, such as will enable others skilled in the art to which it 10 pertains to make and use the same.

My invention has for its object to provide an inexpensive advertising board to be displayed on automobiles and at the same time 15 to serve as a cold protector for the radiator, although this is a secondary consideration. With this general object in view, the invention resides in the specific construction of the device hereinafter fully described and 20 claimed, the descriptive matter being supplemented by the accompanying drawing which constitutes a part of this application and in which:

Figure 1 is a perspective view of the device with the flap thereof in lowered position;

Fig. 2 is a front elevation with the flap raised; and

Fig. 3 is a vertical section on the plane of 30 the line 3—3 of Fig. 2.

In the drawing above briefly described, the numeral 1 designates a sign board formed of a single piece of heavy cardboard of a size and shape to completely cover the 35 front of the automobile radiator upon which it is to be used, it being my intention to manufacture these boards 1 of different sizes and shapes for application to all styles and makes of cars without marring the appearance 40 thereof. At the center of its upper edge and at its lower corners, the board 1 has eyes 2 punched therethrough while at the center of its lower edge it is formed with a substantially rectangular notch 3 to receive the starting crank of the automobile. Substantially midway between its upper 45 and lower edges but preferably spaced closer to the former than to the latter, the board 1 is formed with a plurality of vertically elongated horizontally spaced openings 4 which permit the passage of air to the radiator.

Cords 5 are anchored in the eyes 2 for securing the board 1 in place upon the radiator, this anchoring being preferably done 55 by folding the cords upon themselves, pass-

ing the folds through the eyes and then inserting the free ends of said cords through the looped portions thereof as shown clearly in the drawings. The cords, however, might otherwise be anchored.

A rectangular horizontally elongated flap 6 formed of a single piece of heavy cardboard is hinged at one edge to the sign board 1 adjacent the lower ends of the openings 4, said flap being adapted to swing upwardly 60 over said openings as shown in Fig. 2 to prevent the passage of air therethrough when the car is standing idle. Slots 7 and 8 are formed respectively through said one edge of the flap 6 and the board 1 and strips of 65 metal 9 are passed through said slots 7 and bent upon themselves to form hinges for the flap, the ends of said strips being passed through the slots 8 and clenched to secure them in place. This means of hinging the 70 flap is preferable on account of its simplicity and low cost of manufacture.

A metal eyelet 10 is carried by the edge of the flap 6 remote from the hinged edge thereof, said eyelet coöperating with upper 80 and lower turn buttons 11 and 12 respectively carried by the board 1, these parts serving to hold the flap in either raised or lowered position, although other means could well be employed for this purpose.

The portions of the sign board 1 above and below the openings 4 thereof are used for advertising purposes and although the matter below said openings will be covered by the flap 6 when the latter is lowered, this 90 same advertising matter may be printed on what is then the outer face of said flap as shown in the drawings. The opposed side of the flap may also carry advertising matter as indicated in Fig. 2. I intend to supply different business establishments with the devices printed so as to advertise the articles or merchandise which they have for sale so that they may give one of said devices free of charge with purchases equaling 95 in value any predetermined amount. I also intend to print upon the devices information to the effect that one may be obtained free of charge from the establishment whose advertisements appear thereon and by this 100 means it is believed that the device will be a highly efficient advertising medium.

I claim:

An advertising device comprising a board shaped to cover an automobile radiator and 110

having a vertically swinging flap, said board having advertising matter over which said flap swings when open, said flap having the same advertising matter as that obscured thereby when open and then displaying such advertising matter.

In testimony whereof I have hereunto set

my hand in presence of two subscribing witnesses.

DAVID E. EWING.
